UNITED STATES PATENT OFFICE.

EDMUND MORRIS, OF MICHIGAN CITY, INDIANA.

DESIGN FOR CANE FABRIC.

SPECIFICATION forming part of Design No. 26,856, dated March 30, 1897.

Application filed February 18, 1897. Serial No. 624,049. Term of patent 31 years.

To all whom it may concern:

Be it known that I, EDMUND MORRIS, a citizen of the United States, residing at Michigan City, in the county of La Porte and State of Indiana, have invented and produced a new and original Design for Cane Fabric, of which the following is a specification, and which is illustrated in the accompanying drawing, showing a face view of a small piece of fabric o with my design applied.

Cane fabric containing my design has alternately-arranged narrow close-woven and wide-open mesh stripes A and B. Each stripe A is made up of a series of parallel strips a , 5 arranged close together and divided up into short lengths or sections a' by a series of cross-strips a^2 . Each stripe B has a series of pairs of parallel strips b running parallel with the stripe A, but separated from each other by o regular distances. Each stripe B has also a series of pairs of strips b' , which form continuations of the cross-strips a^2 , and which,

with the strips b and diagonally-arranged strips b^2 , produce in the stripe B a series of rows of octagonal figures x .

The leading feature of my design is the alternately-arranged narrow close-woven and wide-open mesh stripes A and B, the former made up of parallel strips arranged close together and divided up into short sections by 30 cross strips and the latter containing two series of pairs of strips arranged at right angles to each other and crossed by diagonal strips, which thus produce a series of rows of octagonal figures. 35

I claim—

The design for cane fabric, substantially as herein shown and described.

In testimony whereof I have hereunto subscribed my name.

EDMUND MORRIS.
